UNITED STATES PATENT OFFICE.

EVERETT N. MURPHY, OF CHICAGO, ILLINOIS, ASSIGNOR TO STEVENS PARTITION & FLOOR DEADENER CO., OF CHICAGO, ILLINOIS, A CORPORATION OF ILLINOIS.

FLOOR CONSTRUCTION.

Application filed July 17, 1924, Serial No. 726,472. Renewed March 26, 1928.

My invention relates to floor construction of buildings, and has reference more particularly to a known type of sound-proof floor construction wherein the upper or finishing 5 floor is laid upon a series of nailing strips that are seated in chairs, which in turn rest upon and are secured to the lower rough floor, pads or cushions of felt or other fibrous or yielding material being interposed between the bottoms and sides of the nailing strips and the seats and sides of the chairs and forming the sound insulating elements of the structure.

The present invention is an improvement 15 over the type of floor construction disclosed by me in U. S. Patent No. 1,302,578, granted on May 6, 1919.

In my prior disclosure I have provided a novel form of hold down for the nailing 20 strips whereby when there is a tendency for the upper floor to buckle, or swell, as the result of moisture, or the like, the chairs will retain the nailing strips in position through this hold down. This hold down 25 was so illustrated as not to transmit vibrations between floors, nor to neutralize or impair the inherent resiliency of the floor, nor the vibration absorbing quality and capacity of the fibrous insulation.

30 An object of this invention is to provide an improved type of hold down, which is exceedingly simple and cheaper than the former type, which is more convenient and involves less trouble in its assembly, and 35 which is superior and more efficient in use.

It will be hereinafter noted that less skill is required in placing the chair astride the lower edge of the nailing strip and securing it in position by the hold down disclosed 40 herein than the hold down disclosed in my prior patent. No prior work is involved on the nailing strips, nor is time required to lay off the places where the hold down engages the nailing strips, except that the approximate centers be ascertained. The use 45 of special tools required in this work is eliminated, and under the present method of assembling the chairs by the hold downs, nothing more than a hammer need be used.

50 The improved hold down is fool-proof in that it is self centering, i. e. will always properly center itself, so that the non-physical rigid or solid contact between the floor and

chairs will not be impaired by an improperly aligned hold down.

In order to apprise those skilled in the art how to construct and practice my invention, I shall now describe an embodiment thereof in connection with the accompanying drawings forming a part hereof.

In the drawings—

Figure 1 is a fragmentary perspective view of a fire-proof floor construction embodying the present invention;

Fig. 2 is a vertical section taken on line 65 2—2 of Fig. 1;

Fig. 3 is a vertical section taken at right angles to Fig. 2;

Fig. 4 is a view similar to Fig. 2 but illustrating the invention as embodied in a 70 wooden or non-fire-proof floor construction, employing, however, substantially the same bonding or anchoring means; and,

Fig. 5 is a detailed view of the centering 75 means employed herein.

Referring now to the drawings in detail, and describing first Figs. 1, 2 and 3 which show an embodiment of the invention in a fire-proof floor construction, 10 designates the lower rough floor of fire-proof material, 20 such as tiling set in and bonded by concrete, mortar or cement and supported by suitable means (not shown). 11 designates the upper finishing floor that is nailed to the underlying nailing strips 12, these latter 30 being in turn supported at intervals in chairs, each of which in the form herein shown consists of a pair of general U-shape metal members 13 and 14, placed and secured back to back, the upper member 13 35 having an interior lining or cushion 15 of felt, cattle hair, sea grass, or other like fibrous or yielding material secured thereto by wire fastenings 16, which lining or cushion 40 embraces and directly engages the bottom and sides of the nailing strip 12, and the dependent limbs of the lower member 14 terminating in feet 17 that are embedded in slightly raised spots or mounds 18 of concrete or cement formed on the upper surface 45 of the lower rough floor 10. The feet 17 of the chairs may, if so desired, be formed with slots or holes 19, as shown through which the 50 wet concrete or cement flows and when dry, strongly unites the feet of the chairs to the 55 lower floor structure. Casting metal or

stamped one piece chairs may obviously be employed.

As previously mentioned, the seat or central portion 20 of the upper chair 13 and the central portion 21 of the lower chair 14 are placed back to back and suitably secured together. The central portions 20 and 21 are preferably fitted with a central aperture 22, through which suitable means may be employed for anchoring the upper floor 11 to the lower floor 10 through the nailing strips 12. This anchoring means in the present case is in the form of a nail 24, which enters the aperture 22 from the under side and also the nailing strip 12, the nail 24 going into the nailing strip 12 a predetermined distance. The particular type of nail employed is immaterial, but I desire, however, to employ a nail having its surface considerably roughened or cement coated, so that when the nail is driven into the nailing strip it will tightly grip the nailing strip and hold itself permanently therein.

The present invention is concerned mainly with this form of anchoring means for the upper floor 11, and also with a novel centering means used to insure accurate vertical alignment between the nail 24 and the aperture 22 in the chair, the purpose of which will be presently described. This centering means comprises a washer 25 having its center stamped or otherwise formed into an upwardly turned conical or tapering guiding portion 26, the apex of which is fitted with an aperture 27, and the opposite end with a marginal flange 28. The conical portion 26 is adapted to ride in the aperture 22. The nail passes through the aperture 27 of this conical portion 26, and the head of the nail may, if so desired, rest within the conical portion. It may be desired that the base of the conical portion 26, if not the flange 28 alone, be larger than the aperture 22, so that when the nail 24 is driven from the under side into the nailing strip 12, a portion only of the centering washer 25 will enter the aperture 22. It is apparent that these nails 24 may be quickly driven in place, the centering washer in each instance assuring proper vertical alignment of the nails 24 with respect to the apertures 22.

When the chairs are first applied to the nailing strips, or vice versa, and the nails 24 applied, the heads of these nails will bring the conical portions 26 of the washers 25 up into the apertures 22 until they contact with the chairs. But the adjustment is such that when the strips and the finishing floor are laid, the insulating pad or cushion 60 is compressed, permitting the nailing strips and their fastening nails 24 to sink slightly, but sufficiently to carry the centering washers out of contact with the chairs at the apertures 22, so that there is then no rigid, solid or continuous fastening element

or means between the upper and lower floors. Vibrations, and consequently sounds, are therefore not normally transmitted. Likewise, the resiliency of the floor due to the pad and chair supports is not affected. But, on the other hand, if the upper floor swells from moisture or other causes and starts to arch, buckle, warp or otherwise rise from normal level position, the fastening nails arrest such movements practically at their inception, in an obvious manner. When the floors dry out again, the parts return to normal position with the heads of the nails and the centering washers out of contact with the lower sides of the chair seats, thus restoring the sound and vibration insulating conditions.

In the application of the chairs to the nailing strips 12 in practice, the nailing strips are preferably turned bottom up. The chairs are also turned bottom up and positioned astride the then upper edge of the nailing strips which edge is the lower edge when the nailing strips are in position on the floor 10. Washers 25 are then placed in the holes 22 with their conical tips 27 extending into or partway through the holes. The nails are preferably too large to pass freely through the apertures 27 of the washers 25 in order that their points are held in the conical portions 26 ready to be driven by the hammer into the nailing strips. If the pressure of the fingers of the workman does not at once center the nails and washers with reference to the holes 22, the first blow on the nails will do so. Since the force required to drive the nail through the openings 27 of the washers will at once cause the conical portion of the washers to center themselves in the holes 22, the nails are both centered at the start and thereafter guided centrally while being driven into the nailing strips. This is all done automatically, without special care or attention, and with no tools but the hammer.

Each chair is fastened in this way since it is much easier to do it than to employ wires as a temporary fastening, which later have to be cut and removed, as was common with the prior form of hold down construction. This prior form was more laboriously applied and therefore was commonly used on every four or five chairs instead of on each. By this simple means each chair is secured in place and thus a more uniformly applied hold down is afforded. Another advantage resides in the easier handling of the nailing strips after the chairs are thus secured, inasmuch as the chairs are each definitely secured in position. It is merely necessary to turn the strip over whereas if only part of the chairs is permanently secured in place, the others must be wired in place or they are liable to fall off or be displaced in turning the strip over, and some

- are liable not be wired or wired only loosely and thus be displaced. Besides the labor of wiring is considerable and the wiring must be removed before the finishing floor is laid.
- 5 Between the upper and lower floors, a filling 30 of loose dry cinders or similar cellular material occupying the spaces between the nailing strips may be used, if so desired. The nailing strips are preferably 70 elevated above the water, gas and other pipes or conduits, indicated at 31, so as to clear the same and render the cutting of the strips unnecessary in order to lay the pipe and prevent noises.
- 10 15 In Fig. 4, I have shown a similar embodiment of my invention so far as concerns the insulating bonding or anchoring feature, as shown in Figs. 1 to 3, inclusive, but as applied to a non-fire-proof or wooden 75 floor construction of the general type. In these figures, the fire-proof structure of the lower floor 10 of Figs. 1 to 3 inclusive, is replaced by a rough wooden floor structure 32 usually consisting of a rough flooring laid on top of the usual joist 33, on which the feet 17 of the chairs rest and are secured by suitable fastening means, such as nails 34 driven through the holes or slots 19. The nails 24 in this form, are preferably 80 inserted through the chairs and nailing strips in the same manner, the centering means 25 being likewise employed in the same manner to assure perpendicular alignment of the nails with respect to the 85 nail holes in the seats of the chairs. A cinder filling 30 is usually employed, and the nailing strips are raised above the pipes, conduits, etc., 31. In both forms, that is, of Figs. 1 to 3 inclusive, and of Fig. 4 the upper 90 floor is sure to push the nails 24 and washers 25 down, through the nailing strips, so that their lower ends plus the washers are free of the bottoms of the chairs when the nailing strips are in normal position.
- 95 40 45 By this bonding or anchoring means, the nailing strips are prevented from raising to such an extent that the cinders are liable to work therebeneath and thus prevent them from receding in normal position on the 100 chairs when the floor dries out again.
- 50 Without further elaboration, the foregoing will so fully explain the gist of my invention, that others may, by applying current knowledge, readily adapt the same for 105 use under varying conditions of service, without eliminating certain features which may be properly said to constitute the essential items of novelty involved, which items are intended to be defined and secured 110 to me by the following claims.
- 55 60 65 What I claim as new and desire to secure by Letters Patent of the United States, is:
1. In a building floor construction, the combination, with upper and lower floors and sound insulating means for supporting 115
  - the upper floor on the lower floor, of means for anchoring said upper floor to said lower floor, said anchoring means being the only non-cushioned connection and including connected elements normally out of physical contact with each other under the load effect of the upper floor, and which may be drawn into physical contact to positively limit the maximum permissible rise of said floor, and means functioning to hold the connected elements of said anchoring means in proper alignment.
  2. In a building floor construction, the combination, with upper and lower floors, and a nailing strip for said upper floor, of sound-insulating means for supporting said upper floor and nailing strip on said lower floor, and means for anchoring said nailing strip to said lower floor, said anchoring means being the only non-cushioned connection and including connected elements normally out of physical contact with each other under the load effect of the upper floor, which elements may be drawn into physical contact to positively limit the maximum permissible rise of said nailing strip, and means for maintaining said elements in perpendicular alignment with each other during their assembly with said nailing strip.
  3. In a building floor construction, the combination, with a lower floor, chairs secured to said lower floor, pads or cushions in said chairs, a nailing strip seated in said pads or cushions, and an upper floor nailed to said nailing strip, of means for anchoring said nailing strip to said chairs comprising a nail driven partway into said nailing strip and projecting through an opening in said chair of sufficient size to afford clearance of said fastening member in said opening, said nail constituting the only non-cushioned connection and being normally maintained out of physical contact with said chair by reason of the weight of the upper floor, and means for centering said nail with respect to said opening when said nail is driven into said nailing strip.
  4. In a building floor construction, the combination, with a lower floor, chairs secured to said lower floor, pads or cushions in said chairs, a nailing strip seated in said pads or cushions, and an upper floor nailed to said nailing strip, of downwardly extending rigid means on said nailing strip passing through openings in said chairs, and apertured centering members through which said means pass and by which they are guided when inserted through said openings and into said nailing strip.
  5. In a building floor construction, the combination with nailing strips for the upper floor, of cushioned chairs or supports for the nailing strips, and means for anchoring the nailing strips to the chairs or support.

- comprising a washer having a central tapered portion passing through an opening in the seat of the chair or support and a nail driven through the tapered portion of the 5 washer and into the nailing strip, said washer being too large to pass entirely through said opening and said nail being too large to pass freely through the tapered portion of said washer.
- 10 6. In a building floor construction, the combination with nailing strips for the upper floor, of cushioned chairs or supports for the nailing strips, and means for anchoring the nailing strips to the chairs or supports, comprising a washer having a central aperture and a portion extending into an opening in the seat of the chair or support, said washer being larger than the said opening, and a nail passing through said aperture in 15 the washer and driven into the nailing strip.
7. In a building floor construction, the combination with a lower floor, chairs secured to said lower floor, cushioning means for said chairs, a nailing strip, and an upper 20 floor nailed to said nailing strip, of means for anchoring said nailing strip to said chairs comprising a nail driven partway into said nailing strip and projecting through an opening in said chair of sufficient size to afford clearance of said nail in said opening, 25 and means for centering said nail with respect to said opening when said nail is driven into said nailing strip.
8. In a building floor construction, the combination with lower and upper floors 30 and sound insulating means for supporting the upper floor on the lower floor, of means for anchoring said upper floor to said lower floor, said anchoring means being the only non-cushioned connection and including connected elements normally out of physical contact with each other, and means functioning to hold the connected elements of said anchoring means in proper alignment.
9. In a building floor construction, the 35 combination with an upper and a lower floor, means for securing said upper floor to said lower floor in sound proof relation comprising spaced metallic elements having oppositely extending feet adapted to be secured 40 to said lower floor and provisions for receiving the nailing strips of said upper floor including members rigidly driven through said elements into said nailing strips in the assembly of said elements to said nailing strips, 45 and sound proofing material interposed to separate physical contact of the solids of said elements and their parts between said floors.
- In witness whereof, I have hereunto sub- 50 scribed my name.
- EVERETT N. MURPHY.
